UNITED STATES PATENT OFFICE.

LUCIE M. KLINKA, OF MILWAUKEE, WISCONSIN.

KITCHEN UTENSIL.

1,235,038.

Specification of Letters Patent. Patented July 31, 1917.

Application filed April 10, 1915. Serial No. 20,373.

To all whom it may concern:

Be it known that I, LUCIE M. KLINKA, a citizen of the United States, residing at Milwaukee, county of Milwaukee, and State of Wisconsin, have invented new and useful Improvements in Kitchen Utensils, of which the following is a specification.

My invention relates to improvements in kitchen utensils.

10 The object of my invention is to provide a handy implement for general kitchen use, the same being adapted for scraping or cleaning cooking utensils either directly or indirectly through a fabric for which the 15 utensil serves as a holder. My invention is also designed to serve as a lifter for stove lids, cooking vessels and the like, and also as a convenient implement for scraping articles of food, cleaning crevices and corners of woodwork, or operating a mop over 20 the surface thereof.

In the drawings—

Figure 1 is a perspective view of a kitchen utensil embodying my invention.

25 Fig. 2 is a plan view of the same.

Fig. 3 is a longitudinal sectional view, showing the means whereby the tool is employed as a holder for a dish mop or other piece of fabric used for cleaning or washing 30 purposes.

Like parts are identified by the same reference characters throughout the several views.

The holder is provided with a shank A, 35 which is preferably U-shape in cross section with the side walls or flanges flattened outwardly at one end to form with the back a flat scraping blade B. The other end portion D of the tool is slightly curved, crossing 40 the axis of the back portion of the shank A, and the side walls d, d, converge and form with the back a blunt point E, said side walls being drawn slightly inwardly toward each other as shown in Fig. 2.

45 The back of the tool is provided with a hole F, preferably located substantially at the junction of the portions A and D. Another hole G is formed in the back of the tool, substantially at the junction of the 50 shank portion A with the flat scraping portion B. Both ends of the tool are preferably cut off squarely, i. e. at right angles to the line or axis of the back of the shank.

The edges of the members or side flanges 55 d, d, are adapted to serve as scraping edges. These edges are laterally curved but extend

at an angle to the shank portion A to facilitate applying with respect to the bottom of a cooking vessel. The scraper B may also be applied to the walls of a cooking utensil, 60 either the end or the side margins being adapted to serve as scraping edges. When desired, these edges of the member B may be covered by a piece of fabric H, one corner or one end of which may be inserted through 65 the hole G to facilitate retention. The fabric may also be grasped by the hand of the user in taking hold of the shank portion A.

If desired also a piece of fabric may be gathered and inserted between the side 70 flanges of the member A and then drawn toward the tapered end of the tool, whereby the fabric will be wedged between the in-turned side flanges d, d, the fabric being then passed over the point E of the tool and constituting 75 a mop I, as clearly shown in Fig. 3, the hole F being employed when desired to receive a mop I therethrough to assist in its operative retention. Where a piece of fabric is employed to cover either the point 80 E of the tool or the flat scraping blade B, the tool may be used for cleaning corners and crevices of furniture or upon the walls and woodwork of a dwelling. In fact, the tool will be found adaptable for a great 85 variety of uses, which will suggest themselves to the ordinary householder.

I claim—

1. A cleaning utensil for household use comprising a tapered sheet metal plate, 90 folded upon itself longitudinally from near the wider end to the narrower end, and constituting a tool having a rounded back and side flanges, the margins of which are adapted to serve as scraping edges, said side 95 flanges converging each toward the other and tapering substantially to a point at the smaller end, and the back being provided with an aperture near said point whereby a piece of fabric may be engaged in said aperture, folded over the pointed end of the tool and anchored between the converging side flanges by drawing the fabric toward the point of the tool in the channel between said 100 flanges.

2. A cleaning utensil for household use comprising a tapered sheet metal plate, folded upon itself longitudinally from near the wider end to the narrower end, and constituting a tool having a rounded back and side flanges, the margins of which are adapted to serve as scraping edges, said side 110

flanges converging each toward the other and tapering substantially to a point at the smaller end, and the back being provided with an aperture near said point whereby a 5 piece of fabric may be engaged in said aperture, folded over the pointed end of the tool and anchored between the converging side flanges by drawing the fabric toward the point of the tool in the channel between said 10 flanges, the pointed end of the tool being

also curved across the longitudinal axis of the back in a plane extending between the side flanges.

In testimony whereof I affix my signature in the presence of two witnesses.

LUCIE M. KLINKA.
